PROPELLION DRIVE UNIT FOR BOATS

Henry Donald Canazzi, Buffalo, N. Y.

Application May 5, 1950, Serial No. 160,337

10 Claims. (Cl. 115—35)

1

My invention relates to propulsion drives for boats, and more particularly relates to improvements in boat drives wherein a propulsion unit of the drive is secured to the outboard side of a boat and is operably connected to a motor and to operating controls within the boat.

Heretofore, it has been found impractical to provide a small, compact, quiet and efficient stern drive propulsion unit for the reasons that the size of the gears and sundry parts of the drive mechanism and their lubricant reservoir have determined the size of their housing and if small gears and a small reservoir are used to reduce the size of the unit, the heat generated by the small gears at high rotative speeds thins the small volume of lubricant and causes objectionable gear noises. In prior drives no means for maintaining the gear lubricant at a consistency to reduce gear noises at high speeds have been provided so that they have been either large and cumbersome or small and noisy.

In propulsion drives the propulsion unit and the motor have been rigidly secured to the boat so that noises and vibrations generated in operating the drive have been transmitted to and amplified by the boat to an annoying degree.

Furthermore in the installation of prior drives the arrangement of the various services and controls, i. e., the motor cooling and exhaust conduits and the drive unit steering and reversing controls has been such as to require making a separate hole in the boat for each of the service conduits and controls and each hole has required a packing or seal which, only if properly installed and maintained, prevents water from leaking into the boat.

The objects of my invention are to provide a small, compact, quiet and efficient reversible and steerable propulsion drive unit for boats, to provide an attractive appearing housing which encases a drive mechanism, a cooling system for the drive mechanism and reversing and steering mechanism so that by forming a single large installation hole in a boat the drive unit may be readily installed and operably connected to a motor, to cooling and exhaust conduits of the motor, and to steering and reversing controls in the boat; to provide a resilient support for a drive unit arranged to seal the installation hole against the entrance of water and to cooperate with resilient mountings for the motor in isolating noises and vibrations, generated by operation of the drive mechanism or by movement of the unit through water, thus preventing such noises and vibrations from being transmitted to and ampli-

2

fied by the boat hull; and to provide a stern drive unit with a cooling system operably connected to a motor cooling system and in constant communication with an exhaust conduit in a rotatable steering section of the unit.

In the drawings:

Figure 1 is a side elevational view showing my improved stern drive unit mounted in the stern portion of a boat, shown in section, and operably connected to a motor and controls in the boat.

Figure 2 is a rear elevational view of the drive unit shown in Figure 1.

Figures 3 and 4 are enlarged transverse sectional views taken substantially along the lines 15 3—3 and 4—4 of Figure 1.

Figure 5 is an enlarged horizontal sectional view taken along the line 5—5 of Figure 1.

Figures 6 and 7 are enlarged horizontal sectional views taken along lines 6—6 and 7—7 respectively of Figure 1.

Figure 8 is a view similar to Figure 1 but enlarged and having the upper portion of the drive housing broken away to show sundry features of the drive mechanism.

Figures 9 and 10 are enlarged sectional views showing the connections between the shifting mechanism and its flexible control and the connection between the steering mechanism and its flexible control respectively, and;

Figure 11 is a side elevational view of a drive unit similar to Figure 1 but modified to be resiliently connected to the bottom of a boat.

Referring now to the drawings the numeral 20 generally designates a power boat hull having a bottom 21, spaced side walls 22 and a rear wall or stern 23.

A motor 25 is resiliently mounted in the hull for limited oscillatory movement, as by the resilient mountings indicated at 26 with its drive shaft 27 and its fly-wheel housing 28 directed toward and spaced from the stern 23. A single large hole 24 is formed in a wall of the boat, preferably in the center of the stern 23, for the passage therethrough of sundry elements of a propulsion drive unit 30.

In general the drive unit 30 is resiliently secured by a resilient mounting means 40 which isolates noises and vibrations and which preferably seals the installation hole 24 against leakage of water into the boat. The drive unit 30 includes a housing 31 having a rotatable depending propeller carrying steering section 45, and encases a mechanism 60 for rotating the section 45, a reversible propeller drive mechanism 70, a clutch mechanism 90 for controlling the drive

mechanism, and a cooling system 100 for the drive mechanism.

By reason of their encasement by the housing the drive mechanism and the cooling system may be readily extended through the single hole 24 and operably connected to the motor 25 and at the same time the encased reversing and steering mechanisms are also extended through the hole and may be operably connected to suitable controls within the boat.

More specifically stated, and as best seen in Figure 8, the multi-section housing 31 includes an upper section 32, formed with a gear chamber 33 which, being separated from a cooling chamber 34 formed in its lower reduced end portion by a transverse wall 35, is in a heat exchanging relation with the cooling chamber 34. The open top of the chamber 33 is closed by a cap section 36 which is detachably secured to the top of the section 32 by suitable bolts. The section 32 and the cap 36 are each formed with complementary portions which extend horizontally therefrom and, being formed at their outer ends with complementary external flanges 37 and 38, provide a flanged tubular mounting bracket section 39. The tubular section 39 is secured by bolts 41 to a resilient element 42 of the mounting means 40 which in turn is secured to the stern 23 so that the section 32 is spaced from the hole 24 and the outer side of the stern 23. By reason of this manner of resiliently securing the drive unit 30 in spaced relation to the stern 23 and the hole 24 noises and vibrations generated by operation of its drive mechanism or by movement of the steering section 45 through water are isolated by the resilient element and are not transmitted to and amplified by the boat.

Since it is preferred to also utilize the mounting means 40 as a seal for the hole 24, the resilient element 42 is formed of a sheet of strong and tough rubber-like material which is extended to overlie the hole 24 and is secured thereabout by a ring 43 and screws 44 thus providing a simple and effective combined resilient mounting and seal for the drive unit.

The steering section 45 of the casing 31 preferably includes an upper section 46 and a lower section 51 operably connected together by a pivot pin and a shear pin (see Figures 5 and 8) for rotating movement about a common vertical axis and for upward swinging movement of the lower section independently of the upper section and about the horizontal axis of the pivot pin when the lower section encounters an obstacle with sufficient force to break the shear pin. To prevent water from entering the steering section at the juncture of the sections 46 and 51 their abutting surfaces are formed to normally interfit as indicated in Figure 8.

The upper steering section 46 includes an annular body which is formed with a reduced bearing surface 47 concentric with the body and a further reduced tubular bearing boss 48 also concentric with the body and connected thereto by integral radial arms, thus providing through passages between the body and the boss 48 for a purpose to be described later.

The bearing surface 47 is journalled in a flanged bearing 49 secured in the lower end of the reduced portion of the section 32, and the boss 48, being extended above the annular body so that it projects through the cooling chamber 34, the wall 35 and into the gear chamber 33, is journalled in the center of the wall 35 by a radial thrust ball-bearing 49'. A suitable seal is mount-

ed in the wall 35 below the bearing so as to allow the boss 48 to rotate and to seal off communication between the gear chamber 33 and the cooling chamber 34.

The lower section 51 of the steering section 45 includes a tubular body portion 52 which between its bell-shaped upper end 53 and a stream-line hollow enlargement 54 at its lower end is of a flattened substantially elliptical cross sectional shape, and is formed with a rearwardly extending conduit portion 55 below which a horizontally disposed cavitation plate 56 is integrally formed. A plate 57, formed integral with and extended below the enlargement 54 in a plane coincident with the plane of the long axis of the section 51, cooperates with the body 52 in serving as a rudder for steering the boat when the steering section 45 is rotated. A propeller 58 is operably mounted at the rear end of the enlargement 54 with its axis of rotation in co-planar relation with the body 51 and the plate 57, so that when the propeller is rotated its thrust is parallel to the rudder. The thrust of the propeller is thus advantageously used to supplement the steering effect of the rudder in steering the boat. In other words power steering is provided.

To prevent axial movement of the upper section 46 in its bearings 49 and 49' and to provide means for rotating the steering section 45 a worm wheel 61 of the steering mechanism 60 is detachably secured to the inner end of the boss 48, and is retained against the inner face of the bearing by a suitable retainer ring. A driving connection, preferably a key (not shown) is provided between the worm wheel and the boss to insure rotation of the section 45 when the steering mechanism is operated.

In the mechanism 60 for rotating the steering section 45 (Figure 7) a shaft 62 is horizontally disposed and at opposite ends of a worm 63, is journalled in bearing bushings secured in bearing bosses 64 and 65 formed on a wall 33' of the gear chamber 33 so that the worm is in constant mesh with the worm wheel. The shaft 62 is horizontally extended through the wall 33', the tubular bracket section 39, the mounting means 40 and the hole 24, and its enlarged end (see Figure 10) is formed with a squared central bore 66 in which the squared outer end of a flexible drive element 67 of a flexible drive cable 68 is inserted and secured by a set screw 69.

The flexible cable 68 is extended to some convenient location in the boat at which point the flexible element 67 is operably connected to any suitable means for rotating it (e. g. a steering wheel, not shown) so that by rotating the remote end of the element 67 more or less, the shaft 62, the worm 63, the worm wheel 61 and the steering section 45 are likewise rotated more or less, in steering the boat. The construction of flexible drive cables and their mountings are so well known that they need not be further described.

Referring now to the reversible propeller drive mechanism 70 (see Figure 8) a horizontally disposed shaft 71 is journalled in bearings 72 and 73 mounted in the walls of the gear chamber 33 and the cap 36 and is extended through a seal adjacent the bearing 72, the tubular bracket 39 and the mounting means 40. The inner end of the shaft 71 is operably connected to and driven by the drive shaft 27 by any suitable means which allows a slight gyrating or universal movement between the shafts due to slight misalignment of the shafts or slight movement of the resiliently mounted drive unit 30. A suitable spline con-

nection between the drive shaft 27 and the shaft 71 is indicated at 74.

A pair of bevel gears 75 and 76 are freely rotatable in spaced relation on the shaft 71 within the gear chamber 33 and either of the gears may be caused to rotate with the shaft by shifting a clutch body, slidably secured to the shaft, toward the gear to be rotated. The clutch may be of any suitable type, however, for the sake of compactness, capacity and smoothness of operation it is preferred to use a multiple disc type of clutch, wherein a series of clutch discs are slidably secured to opposite ends of the clutch body and are internested in alternate relation with a series of clutch discs slidably secured in tubular concentric extensions of the gears 75 and 76.

The internested series of clutch discs, as indicated by dotted lines at 75' and 76' in Figure 8, normally have no driving effect when the clutch body is in its neutral position midway between the gears, but when the clutch body is shifted toward the gear 75 the associated series of clutch discs 75' are engaged and the gear 75 is driven, and when the clutch body is shifted toward the gear 76 the associated series of clutch discs 76' are engaged and the gear 76 is driven.

The bevel gear 75 and 76 are in constant mesh with diametrically opposite sides of a bevel gear 77 secured to the upper end of a vertically disposed shaft 78 which is extended through the bore of the boss 48 and is journaled in suitable bearings secured in counterbores in its upper and lower ends so that upon shifting the clutch in the above described manner, the gear 77 may be rotated in opposite directions. The bevel gears 75, 76, 77, the worm wheel 61 and the worm 63 are lubricated by operating in a suitable oil in the gear chamber 33 and since the chamber 33 is in heat exchange relation with the cooling chamber 34 of the cooling system 100 the oil is cooled and the gears operate quietly. Leakage of oil from the chamber 33 into the cooling chamber 34 is prevented by an oil seal secured in a counterbore in the boss 48 below the upper bearing and by a seal below the bearing 49 in the wall 35.

At the juncture of the sections 46 and 51 companion jaw clutch elements 81 and 82 are secured respectively to the adjacent ends of the shaft 78 and a shaft 79 journaled in the center of the section 51 in coaxial alinement with the shaft 78. The clutch elements 81 and 82 are normally engaged for the transmission of power between the shafts and when the shear pin is broken and the section 51 is swung about the axis of the pivot pin, as described above, the clutch elements are separated and transmission of power between the shafts is cut off.

The shaft 79, being thus normally connected to the shaft 78 by the clutch elements 81 and 82, has its upper end journaled in a bearing secured in a boss 83 formed in the center of the bell shaped portion 52 and inwardly spaced therefrom by integral radially disposed legs 84, thus providing passages therebetween for a purpose to be presently described, and has its lower end journaled in a bearing 85 secured in the section 51 at its juncture with the enlargement 54. A bevel gear 86 is secured to the lower end of the shaft 79 and meshes with a bevel gear 87 secured to a shaft 88 which drives the propeller 58. The shaft 88 is horizontally disposed and journaled in the center of the enlargement 54 by spaced bearings 89 secured in the enlargement, and being projected rearwardly beyond the enlarge-

ment is secured in the hub of the propeller by any suitable means.

In the mechanism 90 for controlling the drive mechanism 78 (see Figure 6) and thus reversing the rotation of the propeller 58, a shaft 91 is arranged in spaced parallel relation to the shaft 71 and is slidably mounted in a bushing secured in a boss 92 formed on the wall 33'. A fork 93 being secured to the end of the shaft 91 located within the chamber 33 is formed to engage in a circumferential groove formed medially of the clutch body so that by shifting the shaft 91 the clutch may be shifted between a non-operative (neutral) position and either of its operative positions described above. The shaft 91, being extended beyond the boss 92 and through the tubular bracket 39, the mounting means 40 and the hole 24, has its opposite end formed with a central bore 94 in which one end of a flexible push-pull wire 96 of a flexible cable 95 is secured by a set screw 97 (see Figure 9).

The cable 95 is extended into the boat and, near the point previously selected for the location of a steering wheel, the other end of the wire 96 is operably connected to a suitable hand lever (not shown).

Since the shaft 71, as viewed from its splined end, rotates in a clockwise direction it will be seen that the arrangement of the drive gears and the blades of the propeller 58 are such that when the wire 96 is pulled to clutch the gear 75 to it, the boat will be driven forwardly, and when the wire 96 is pushed to clutch the gear 76 to the shaft 71 the boat will be driven rearwardly. By combining the reversible propeller drive mechanism with the power steering rudder, in the above described manner, steering and control of the boat is improved considerably.

Referring now to Figure 1 the motor 25 drives a water pump P which is supplied with water by an intake conduit I and which, by suitable connections, pumps water through the motor block, through a conventional gas and water exhaust manifold M and into a combined exhaust gas and water conduit E.

The cooling system 100 for the drive mechanism includes a water intake conduit 101 which, being extended from a point below the bottom of the boat passes through the mounting bracket 39 and has its inner end operably connected to the intake conduit I by a conduit 102, thus supplying cooling water to the pump P. After leaving the exhaust manifold M the exhaust gases and water are mixed in the exhaust conduit E and, by means of a conduit 103 operably connected to the conduit E and to a conduit extension 34' of the cooling chamber 34, are directed into the cooling chamber 34.

As best seen in Figure 7, the conduit 34' is formed in the bracket section 39 to one side of the fore and aft center of the cooling chamber 34, whereby the exhaust water and gases are caused to swirl in passing therethrough, thus increasing their cooling effect on the plate, the oil and the mechanism in the chamber 33. If desired, a further cooling effect may be obtained by providing the external wall surfaces of the chamber 33 and the cap 36 with suitable cooling fins in the manner shown in the drawings.

Referring again to Figure 8 it will be seen that, regardless of the position to which the rudder section 45 may be rotated in steering the boat, the passages formed in the sections 46 and 51 and the conduit 55, are in constant communication with the cooling chamber 34 and provide for the

continuous passage of the exhaust gases and water therefrom. Since the exhaust gases and water leave the steering section 45 at the rear end of the conduit 55 which is normally submerged, exhaust noises are muffled by the water and by reason of the conduit 55 being arranged in coplanar relation with the steering section any propulsion effect exerted by the exhaust on the water is utilized in steering and propelling the boat.

It will be obvious that a drive unit so constructed and resiliently secured to a boat and operably connected to the drive shaft and the cooling system of the motor 25 and to controls within the boat, in the above described manner, will satisfactorily perform its intended functions. However, it is preferred to rigidly connect the resiliently mounted motor 25 to the resiliently mounted drive unit 30 by a rigid tubular connecting section 105 to provide a complete resiliently mounted propulsion drive unit for boats.

Accordingly, the section 105 is formed with a tubular body 106 having a bell-like enlargement 107 at one end and an external flange 108 at its opposite end. The enlargement 107 complements the fly-wheel housing 28 and is rigidly secured thereto by suitable bolts and the flange 108, being formed to complement the flange 37-38 is secured thereto by the bolts 41 with the resilient element 42 interposed and clamped tightly therebetween. The section 105 (see Figures 6, 7 and 8) serves to encase and maintain the shaft 71 in operable aligned engagement with the drive shaft 27, and since, end portions of the control cables 68 and 95 and portions of the conduits 102 and 103 pass through holes into the body 106 and are secured therein in alignment with the shafts 62 and 91 and conduits 101 and 34' respectively the section 105 also serves to encase the cables, shafts and conduits and to maintain them in operable alignment.

The enclosed ends of the cables 68 and 95 are secured in the section 105 in alignment with the shafts 62 and 91 by any suitable mounting means (not shown). It is presently preferred that the enclosed ends of the conduits 102 and 103 respectively be secured in spaced holes formed in a coplanar inward extension 111 of the flange 108 as by swaging their ends (see Figures 3, 7 and 8). The ends of the conduits 102 and 103 being anchored in this manner are aligned with the conduits 101 and 34' and to prevent leakage at their junctures a suitably formed gasket 42' which may be formed as an inward extension of the resilient element 42 is tightly clamped between the adjacent faces of the extension 111 and a similar coplanar extension 37' of the flange 37 when the flanges are bolted together.

A hand hole 112, being formed in the top of the body 106, provides access to the section 105 and facilitates operably connecting the driven shaft 71 to the drive shaft 27, the steering mechanism shaft 62 to its control cable 68, and the reversing mechanism shaft 91 to its control cable 95, in the above described manner. The hand hole 112 is normally closed by a cover plate 113 detachably secured thereto as by suitable screws.

In the modified form of the complete unitary propulsion drive, shown in Figure 11, parts which are identical with above described parts are given the same reference numerals and parts which are modified, but which otherwise correspond to previously described parts, are designated by the same numeral with a small figure 2 as an exponent.

Accordingly the upper section 32² of the unit 30² is extended below the motor 25 and projects through a hole 24 formed in the center of the bottom 21 near the stern 23. And, the bearing 49², located between the section 32² and the steering section 45, is formed with a wide flange disposed eccentrically with respect to the section 32² so as to extend laterally beyond it and the intake conduit 101². The flange is spaced from the hole 24 and serves as a mounting bracket for the unit 30² and as to its size and the location of its bolt holes, is preferably a duplicate of the flange 37-38 so that the resilient element 42 of the mounting means 48 may be secured to it and to the bottom of the boat substantially in the manner described above in connection with the mounting of the bracket 39 to the stern 23, thus providing a combined resilient mounting for the unit 32² and a seal for the hole 24 in the bottom of the boat.

The intake conduit 101² terminates above the steering section 45 so that the latter may be rotated through a full circle (360°) by operating the control cable 68 and for this reason the reversing gear 76 and its clutch 76' used in the drive unit 30 need not be used in the drive unit 30². Except as noted the construction and operation of the modified form of propulsion drive is the same as the first form described above.

It should be understood that the forms of propulsion drives shown and described are intended to exemplify the principles of my invention and that various rearrangements and modifications may be made within the scope of the appended claims.

I claim:

1. In a propulsion drive unit for boats; a housing; a propeller carrying rudder section rotatably secured to the housing; a propeller drive mechanism operably mounted in the housing and in the rudder section; a cooling system for the drive mechanism comprising a water intake conduit in the housing, and a combined exhaust water and gas conduit in the housing in heat exchange relation with the drive mechanism and in constant communication with a combined exhaust water and gas conduit in the rotatable rudder section; a mechanism for controlling the drive mechanism; and a mechanism for rotating the rudder section; said mechanisms and said cooling system conduits being encased by and extended beyond said housing for extension through a single hole in an exterior wall of a boat and being operably connectible respectively to a drive shaft and to a cooling system of an internal combustion motor and to control means mounted within the boat; and means for resiliently supporting said housing in spaced relation to the walls of the hole and the boat; whereby noises and vibrations generated in operating the drive unit and by movement of the rudder section through water are isolated by the resilient supporting means.

2. The combination set forth in claim 1 wherein in the resiliently supported housing is extended through the single hole and its inner end is rigidly securable to a motor resiliently mounted in the boat and the resilient supports for the housing and motor cooperate in isolating noises and vibrations.

3. The combination set forth in claim 1 wherein in the resilient supporting means for the drive unit is sealingly secured to said housing and to said wall beyond said hole, whereby said support

also serves as a seal for preventing water from entering the boat and the drive unit housing.

4. The combination set forth in claim 1 wherein the resilient means is formed as a resilient gasket having its inner margin sealingly secured to the housing and its outer margin extended beyond the hole and sealingly secured to the wall to close and seal the space between the housing and the wall against leakage of water therethrough and said gasket is extended inwardly from its inner margin and clamped between the adjacent ends of the intake and exhaust conduits to prevent intake water and the combined exhaust water and gases from leaking into the housing.

5. The combination set forth in claim 1 wherein in the propeller drive mechanism includes mechanism for reversing the direction of rotation of the propeller, and wherein the outlet of the combined exhaust water and gas conduit being normally submerged in water is arranged with its axis in coplanar relation with the steering section to utilize any propulsion effect of the combined exhaust on the water in steering and propelling the boat.

6. The combination set forth in claim 1 wherein in the combined exhaust water and gas conduit of the cooling system is operably connectable to the combined exhaust water and gas conduit of an internal combustion engine and enters one side of a cooling chamber in the housing in heat exchange relation with a gear chamber of the drive mechanism, thereby causing the exhaust gases and water entering the cooling chamber to swirl in the chamber for more effective cooling of the gear chamber before passing into and through the exhaust conduit in the rotatable rudder section.

7. A propulsion drive unit for boats comprising an internal combustion motor resiliently mounted in the boat; a housing; a propeller carrying rudder section rotatably secured to the housing; a propeller drive mechanism operably mounted in the housing and in the rudder section; a cooling system for the drive mechanism comprising a water intake conduit in the housing, a combined exhaust water and gas conduit in heat exchange relation with the drive mechanism and in constant communication with a combined exhaust water and gas conduit in the rotatable rudder section; a mechanism for controlling the drive mechanism; a mechanism for rotating the rudder section; said drive mechanism, said cooling system and said controlling and said rotating mechanisms being encased by and extended through said housing and being operably connected respectively to the motor drive shaft, to the motor cooling system and to control means within the boat, said housing being rigidly connected to said motor and freely extended through a single hole in a wall of the boat for submersion of its rotatable rudder section in water; and a resilient support means for the housing cooperating with the resilient mountings of the motor in isolating noises and vibrations generated in operating the drive unit and

by movement of the rudder section through water.

8. The combination set forth in claim 7 wherein in the housing is formed of inner and outer sections and the resilient supporting means is formed as a resilient gasket having its inner margin interposed and tightly clamped between inner and outer sections of the housing and between the aligned opposite end walls of the intake and exhaust conduits to prevent transmission of noises and vibrations and leakage of water therebetween, and to prevent leakage of intake water and the combined exhaust water and gases from said conduits and into the housing, and having its outer margin extended beyond the sections and the hole and sealingly secured to the wall, thereby preventing water from leaking into the boat.

9. The combination set forth in claim 7 wherein 20 in the combined exhaust water and gas conduit of the cooling system enters one side of a cooling chamber in heat exchange relation with a gear chamber in the housing, thereby causing the exhaust gases and water to swirl in the cooling chamber for more effective cooling of the gear chamber before passing into and through the exhaust water and gas conduit in the rotatable rudder section.

10. In a propulsion drive unit for boats; a 30 housing; a propeller carrying rudder section rotatably secured to the housing; a propeller drive mechanism operably mounted in the housing and in the rudder section; a cooling system for the drive mechanism comprising a water intake conduit in the housing, and a combined exhaust water and gas conduit in the housing in heat exchange relation with the drive mechanism and in constant communication with a combined exhaust water and gas conduit in the rotatable rudder section; a mechanism for controlling the drive mechanism and a mechanism for rotating the rudder section; said mechanisms and said cooling system conduits being encased by and extended beyond said housing for extension 40 through a hole in an exterior wall of a boat and being operably connectible respectively to a drive shaft and to a cooling system of an internal combustion motor and to control means mounted within the boat; and means for operably supporting said housing on said external wall of the boat.
